US00D905852S

(12) **United States Design Patent** (10) Patent No.: **US D905,852 S**
(45) Date of Patent: **** Dec. 22, 2020**

(54) **DRAINAGE BAG OUTLET INCLUDING CLOSURE**

(71) Applicant: **Hollister Incorporated**, Libertyville, IL (US)

(72) Inventors: **Anthony Scalise**, Libertyville, IL (US); **Jan Torstensen**, Virum (DK); **Brock E. Masters**, Des Plaines, IL (US); **Claire O'Grady**, Castlebar (IE); **Elizabeth M. Starck**, Villiage of Lakewood, IL (US); **Ashish Trivedi**, Gurnee, IL (US); **Alexander Nikon**, Arlington Heights, IL (US); **Sara Wegener**, Libertyville, IL (US)

(73) Assignee: **Hollister Incorporated**, Libertyville, IL (US)

(**) Term: **15 Years**

(21) Appl. No.: **29/699,069**

(22) Filed: **Jul. 23, 2019**

(51) LOC (12) Cl. **24-02**

(52) U.S. Cl.

USPC **D24/129; D24/108**

(58) **Field of Classification Search**

(57) **CLAIM**

The ornamental design for a drainage bag outlet including closure, as shown and described.

DESCRIPTION

FIG. 1 is a top, front perspective view of a drainage bag outlet including closure embodying our new design;

FIG. 2 is a front view thereof;

FIG. 3 is a rear view thereof;

FIG. 4 is a side view thereof as seen from the right-hand side of FIG. 2;

FIG. 5 is a side view thereof as seen from the left-hand side of FIG. 2;

FIG. 6 is a top view thereof; and,

FIG. 7 is a bottom view thereof.

Portions of the drainage bag outlet including closure shown in phantom lines in FIGS. 1–7 form no part of the claimed design.

1 Claim, 5 Drawing Sheets
